UNITED STATES PATENT OFFICE.

MORRIS SCHOENFELD, OF RORSCHACH, SWITZERLAND.

EMBROIDERING-MACHINE.

1,024,911.

Specification of Letters Patent.

Patented Apr. 30, 1912.

Application filed February 16, 1910. Serial No. 544,195.

To all whom it may concern:

Be it known that I, MORRIS SCHOENFELD, a citizen of the United States, and a resident of Rorschach, in the Canton of St. Gall, Switzerland, have invented certain new and useful Improvements in Embroidering-Machines, of which the following is a specification.

The present invention relates to the construction of embroidering machines wherein several hundred needles simultaneously operate to produce embroidery upon a fabric and the object thereof is to completely revolutionize the construction of such machines.

The present invention not only relates to the structural features of the machine, but also to certain mechanisms, while other cases being filed by me embody mechanisms especially adapted for the present structures.

It is my object to entirely improve the structure of the machine, but to preserve the present arrangement, in so far as the arrangement of the needles and other mechanisms on one side of the fabric and the shut-

25 tles on the other, is concerned.

The principal features of the present case are in the arrangement of the framework. Heretofore the framework of an embroidering machine was constructed generally of four heavy cast iron horizontal beams which were rigidly attached at both ends to vertical frame posts or standards. Of these four beams two were invariably arranged in front and adapted to carry the needle and other devices necessary on the front of the work to be embroidered; while the other two beams were on the rear side and were equipped with the mechanism for the operation of the shuttles and such other mech-

30 anism as operated from the rear of the fabric. From this type which has hitherto been generally used, the present invention is distinguished particularly by the fact that the numerous working mechanisms are not

35 carried primarily by heavy longitudinal beams but by a number of upright posts, or frames, arranged at comparatively short distances apart parallel with each other and transverse of the longitudinal direction of the machine. The groups of embroidering tools and their mechanisms may be secured either directly or indirectly to these upright frame sections.

The objects of such novel arrangement are 40 manifold. A clear view of the fabric is afforded to the operator through the machine

frame, so that the operator and attendants in charge of the machine have a less obstructed view of the embroidery surface whereas hitherto a large portion of the embroidery surface has been covered by the heavy frame beams.

Another object is to make it possible to provide more than two rows or series of needles, one above the other. In the accompanying drawings a machine is shown having six rows of needles and sewing implements. Hitherto this increase has been impossible for the reason that for each row of needles special beams had to be provided, which, owing to their great length and the weight carried by them between their points of support were comparatively large. If more than two beams were arranged one above the other hardly anything could be seen of the embroidery surface, and the manual manipulation of the parts between the beams for the purpose of arranging the various devices and threads would be im- 50 possible.

Another important advantage of my invention is that the rows of needles and the associated mechanisms in the front of the machine and the shuttles or other mechanisms in the rear can be adjusted in vertical direction, whereby the sewing can be performed at various positions upon the fabric. That is the rapport rows can be made more or less remote from one another. Hitherto this adjustment has been impossible because 55 the positions of the various groups of tools was necessarily a determined factor owing to the position of the heavy longitudinal beams referred to and also because of the difficulty of adjusting such a cumbersome arrangement of mechanism. As the longitudinal supporting beams formed a constituent part of the machine frame, it was impossible to change their connections with the vertical portions of the frame, to secure vertical ad- 60 justment of the mechanisms.

In the present invention the various mechanisms are supported by vertical frame members, as distinguished from longitudinal frame elements which are themselves supported at the ends of the machine by frame members. The present invention embodies a number of features which may be used in a single machine as herein shown, but some of the features may be advantageously used 65 separate from the others.

The present invention does not necessarily

eliminate longitudinal frame members, but where they are here used they are for connecting the various vertical frame members to provide a rigid whole, rather than to directly support the working mechanisms, and they are positioned where they will not obstruct the embroidery surface.

Various other advantages will be apparent from the detailed description herein-after.

In the drawings forming a part of this application, Figure 1 is a cross section through the frame of an embroidering machine showing my invention in one of its forms. Fig. 2 is a side elevation of one end of the machine frame, with the mechanisms omitted for simplicity in illustration, Fig. 3 is a cross section of a frame showing a variation in the construction, wherein the upright frame element is in the form of a single casting. Fig. 4 is a side elevation of one end of the frame with the form of construction the same as in Fig. 3, Fig. 5 is a cross section of a frame embodying still another form of construction, Fig. 6 is a side elevation of one end of the frame shown in Fig. 5, Fig. 7 is a cross section of the frame, showing how the operating elements for producing the embroidery may either have permanent positions upon the upright frame members or may be adjustable in vertical relation, the latter embodying my invention more fully, Fig. 8 is a side elevation of one end of the frame illustrating several ways in which the operating elements may be vertically adjusted upon a frame of the form shown in Fig. 7, Fig. 9 is a cross section of a frame embodying a still different modification in structural details and in which additional features of my invention are shown, Fig. 10 is a view similar to Fig. 9, showing my invention carried to a higher point of development, wherein the embroidering elements are vertically adjustable on the frame, Fig. 11 is a detail view showing certain operating mechanism, Fig. 12 is an elevation of a modified form of tension device, Fig. 13 is a cross section of the rear of the vertical frame of Fig. 10, showing one way of vertically adjusting the shuttle track or guide, Fig. 14 is a horizontal section showing the location of parts of the mechanism of Fig. 10, and Figs. 15 and 16 are diagrammatic views illustrating several ways of distributing the sewing mechanisms to give a clear view of the embroidery surface.

In the several views of the drawings I have omitted much of the mechanism which may be of the well known construction, for the purpose of simplifying the present case, such as the fabric frame and its operating mechanism.

In the present invention the structural frame features form an important part and

the same may be combined with the additional mechanical features herein shown, but these frame features may be advantageously used with other mechanism without departing from the broad spirit of my invention, though I prefer to employ either the particular mechanism herein shown or other mechanism conforming to the broad spirit of my invention.

In the present invention the devices or mechanisms for producing embroidery upon a fabric are shown as supported directly or indirectly upon upright frame members. These mechanisms may extend the length of the frame of the machine and be supported at various places along their length by the upright frame members; or they may be connected to long rails or longitudinal connections which are themselves supported throughout their length by the vertical frame members, but these rails, owing to the small load which they are required to support between any of their vertical points of support by the upright frame members cannot be considered as carriers or beams in the same sense as the beams of former constructions. On the other hand the operating elements may be formed in groups, the several groups being independently arranged between the various upright frame members and operated from a common source of operation to make them operate in unison. Where long rails are used to support mechanisms they are of considerably less depth than the carrying beams of former constructions whereby a clear view of the embroidery surface may be had by the operator or attendants during the embroidering operation, and this is possible because of the upright frame members which take up the load and shocks exerted by the various operating parts. Where the longitudinal rails are not interposed, the upright frame members likewise take up the weight and shocks. In a broad sense the result produced in either case is similar, because the upright frame members carry the load at various points throughout the length of the machine and receive the shocks. Where in former machines the operating elements are directly supported upon longitudinal beams and the shocks transmitted by them to the extreme ends of the machine the vibrations are intensified.

In the form of frame shown in Figs. 1 and 2 I have provided upright end frame elements 1, only one of which is shown, it being understood that the same is duplicated at the opposite end of the machine; and between these upright frame members I have provided at various, and preferably regular, intervals upright frame members 2 upon which the weight and shocks of the operating elements are adapted to come. In the drawings only two of these intermediate

frame members are shown, but it is understood that these are multiplied to carry the length of the machine to any desired extent, which may be greater than former machines, and which may extend as far as power can be uniformly supplied to the operating elements. These upright frame members and the end frame members may be connected in various ways to form a rigid whole of the frame, but the elements for connecting these various members are so disposed as not to interfere with the clear view of the embroidery surface. In the form now considered I have constructed the upright frame members of a plurality of sections 3 and 4 preferably of thin metallic plates, easily cast or otherwise formed, having flanges 10 at their base which rest upon the floor which supports the machine; and at the top they are arched toward each other at 11 to form an intermediate space in which the longitudinal tambour frame and fabric are adapted to operate and wherein the embroidering elements are partly disposed. The arch portions 11 I have provided with lateral abutting flanges 12 by which the members 3 and 4 firmly abut against each other. In the present showing the longitudinal rigid connecting means referred to consists of a series of short tubes 8 and 9 abutting against the opposing sides of the various upright frame members, near the base, and these several tubes are connected with each other by connecting bars 13 (see Fig. 2) of reduced diameter, which pass through apertures in the frame members and connect the ends of the adjoining tubes. At the top of the frame I have provided a longitudinal beam 5 which is preferably secured by the bolts 7 to the flanges 6 of the several upright frame members whereby a rigid frame is formed. For this longitudinal beam 5 various forms of commercial iron or steel may be advantageously used, to make the construction simple, strong and inexpensive.

The frame constructed as above forms a rigid whole, having a longitudinal space for the tambour frame and its fabric which may be of any well known construction but which is not made a part of the present case. In this showing I have illustrated how the needle bars 14 may be arranged one above the other in greater numbers than heretofore, in this form as many as six needle bars being shown arranged one above the other; and these bars have laterally extending shafts 15, arranged at various places therealong which move laterally of the machine in guiding sockets or lugs 16 formed on the various upright frame members; and the needle bars preferably terminate within the longitudinal limits of the machine as defined by the end members 1. It will be

seen that this arrangement permits the needle bars to be reciprocated toward and from the fabric to cause the needles to produce the necessary stitching thereon. The shuttle tracks 17 which guide the shuttles are shown secured to the rear portions 3 of the upright frame members by angle plates 18, opposite the several needle bars, whereby the shuttles may be operated in conjunction with the needles of the several needle bars.

Before passing to the embroidering mechanism I will describe some of the modified forms in which my invention, in so far as the frame construction is concerned may be embodied.

In Figs. 3 and 4 the upright frame members 19 are formed each of one component piece, and these are all secured to a common base plate 21, and at the top they are connected to each other by the arched spacing beams 20, the ends of which abut against each other and are bolted to the several frame members to produce a rigid frame structure. In this showing there are provided T bars 22, bolted between the opposing frame members, which support the several needle bars 23 at various points throughout their length instead of by means of the integral lugs on the frame members as previously described. These bars 22 may be small enough to prevent any material interference with a clear view of the embroidery surface and they are not to be considered as the equivalent of the longitudinal beams of former constructions.

In Figs. 5 and 6 the upright frame members are composed of a pair of separately formed plates 24, 25, for the front and rear which are united at the top by a tie plate 26, by means of the bolts 27 and they are secured at their base to a base plate 21, common to the several frame members. In this construction the needle bars and other mechanisms as desired are supported upon tubular connections 28 which engage between the sockets 29 on the opposing sides of the several frame members. These tubes not only tend to support the operating parts but they also serve as spacers for the upright frame members. The upper portions of the various frame members are longitudinally tied by means of a tie rod 29^a inside a tube 30, the nuts 31 on the ends of the tie rod and outside of the frame ends serving to clamp the parts together.

In Figs. 7 and 8 I have shown further steps in my invention the purpose here being to illustrate the use of my frame construction with the various mechanisms having either a fixed relation upon the frame or adjustable, the latter being a fuller embodiment of my invention. The frame construction I have here shown is similar to that in Figs. 1 and 2 and the parts thereof are similarly numbered. The upper rows of

needle bars in Fig. 7 correspond with the showing in Fig. 1 while the two lower rows show how the needle bars (and other mechanism) may be vertically adjusted for the purpose of forming the rows of embroidery at varying distances apart on the fabric 32. These alterations are desirable where it is necessary to operate the machines for various kinds of work, such as handkerchiefs, neckwear etc. The needle and related mechanisms may be adjusted in a vertical direction to place the various rapport rows of embroidery at equal distances, or the various rows may be placed with varying distances between them to suit the requirements. The four top rows of needle bars in Fig. 7 and the third row of Fig. 8 have an unalterable position, while the remaining rows are made adjustable in several different ways. In the fifth row the angle metal bars 33 are secured between the various upright frame members by means of bolts 34 which engage in the apertures in the depending brackets 37 of the bars 33 and in slots 35 of the uprights and the upward ears 36 form the sockets in which the shafts 15 of the needle bars are guided. The position of the needle bar may be vertically adjusted by means of this bolt and slot connection of the supporting bars 33 with the frame members. In the sixth row the form of construction is varied by providing round tubes 38 to which the sockets 39 for the needle bar shafts are secured. In the top row of Fig. 8 the adjustment is made by means of the brackets or sockets 40 which are adjustably connected directly to the frame. The bolt 41 passing through an ear 42 on the frame is threaded through the bracket 40 and by turning the bolt the vertical position of the needle bars are adjusted. The set screw 43 will prevent any change in the adjustment during the operation of the machine. In the second row the brackets are secured to the frame by a bolt 44 which engages in a slot 45 in the frame whereby vertical adjustment may be made. In the fourth row this is slightly varied by a plurality of holes 50 which take the place of the slots of the second row. These show how the manner of adjustment may be varied under the broad scope of my invention and many other means of adjustment may be conceived. In Figs. 9 and 10 I have carried the illustration of my invention further by showing the application of my improved embroidery mechanism to a machine of my improved type and in doing so I have illustrated a modified form of frame construction. In these views I have shown the embroidering devices with a vertical fixed position, and also having means for vertical adjustment, the latter embodying more fully the features of my invention. In this construction I have

shown a modified form of frame though it is understood that the mechanism is applicable to the previously described forms and others. I have employed quite large upright end sections 47 and these support the longitudinal beams 48, 49, 50 and 51 between them, which beams may be of commercial forms of angle metal. Between these beams I have arranged, in pairs, the intermediate upright frame members, which I have shown built up of commercial forms of metal. The front half 52 of the sections are composed of riveted metal bars, and are disposed between the beams 48 and 49, while the rear half 53 is composed of an I beam disposed between the beams 50 and 51. This form embodies the broad principles of construction carried through the entire case and makes the multiplication of needle mechanism possible.

In Fig. 9 the mechanisms are shown with a fixed vertical position but embodying the broad principles of distribution of power to the mechanisms and the mechanisms themselves. The mechanism here shown as an example is the needle mechanism on the front of the machine, it being understood that the principles involved in this may be employed for other tools. It may be first stated that the longitudinal shuttle tracks 17 are suitably connected along their length to the rear elements 53 in such positions as to coöperate with the mechanisms on the front of the machine. On the front side of the fabric 32 I have arranged the various needle bars, tension, spool racks, take up etc., in rows, one set above the other, and disposed so that the support thereof is taken up by the frame members, and they are operated from a common source of power. The shaft 54 is the drive shaft for distributing the operating force throughout the machine for the various mechanisms and from this shaft the power is transmitted to upright driving members preferably by means of cams 55 distributed along the shaft, having peripheries formed according to the requirements of the various elements operated thereby.

In Fig. 9 there are castings or brackets 56 arranged on the several upright frames to provide supporting means for the needle bars etc. The needle bars 14 are disposed longitudinally of the machine, in front of the fabric, and preferably have lateral shafts 15 which engage in sockets forming a part of the brackets 56, whereby the needle bars may be moved to and from the fabric to cause the many needles to stitch the fabric. These shafts 15 are fulcrumed to links 58 which in turn are fulcrumed to the bellcrank lever 59. The link 58 is suitably fulcrumed to the frame to rock preferably vertically, whereby the power nec-

essary to operate the needle bar is derived from the cam on the main shaft 54 by means of an upright pitman 60 having a roller which is held in contact with the periphery 5 of one of the cams 55 by means of a spring 61. The various pitmen 60 are connected with the various bellcrank levers 59 of each tier, causing the various needle bars to move in unison and I prefer to provide a 10 driving arrangement such as described, on each of the upright frame members, whereby the needle bars will be all driven uniformly throughout their length. I have also secured to the brackets 56 the bobbin 15 holders 61^a, for holding the bobbins of thread, preferably immediately below the needle bars and from these bobbins the threads pass around the tension or let off rolls 62, the axles 63 of which are journaled 20 in the brackets 56, preferably on a longitudinal line with the needle bar to obstruct as little as possible the view of the embroidery surface. From the tension roller the threads pass over the take up bars 64, which 25 rock on the arms 65 fulcrumed by shafts 66 to the brackets 56. Extending forward from the shaft 66 is an arm 67 which connects with a pitman 68. The latter is operated 30 from the shaft 54 by means of one of the cams 55 in a similar way to the pitman 60 but the extent and time of movement is such as to give a proper movement to the take up bars 64.

It will be apparent that the mechanism 35 is properly and uniformly driven throughout and because of the disposition of the parts it is possible to view the embroidery surface while employing a larger number of needle bars arranged one above the other.

40 In Figs. 10, 13, and 14 the mechanisms are shown vertically adjustable. Instead of the brackets 56 having fixed positions they are adjustably secured by means of the bolts 69 which engage in the slots 70 45 by which the brackets may be adjusted to change the relative positions of the embroidering mechanisms. This necessitates an adjustment in the operating parts and I therefore connect the bellcrank levers 59 to the pitman 60, by means of bolts 72 50 engaging in slots 71, whereby the connections may be adjusted; and the lever 67 is similarly connected to the pitman 68 by means of the bolt 73 engaging through the slot 74.

55 In Fig. 10 I have also shown a detent mechanism which is adapted to press the detent fingers upon the fabric, near the needles, and against the shuttle tracks. The brackets 56 in this instance have arms 75 60 projecting toward the fabric on which are mounted the shafts 76, carrying the detents 77 which are adapted to press the fabric against the shuttle tracks. The shafts 76 are provided with a lever 78 which in turn 65 is fulcrumed to a link 79; and this link in

turn is fulcrumed to a bellcrank lever 80, suitably mounted to operate the detents. The pitman 81 which is operated similar to the pitmen 60 and 68, from the shaft 54, is adjustably connected with the bellcrank 70 lever 80, by means of the bolt and slot connection 82, 83, whereby the detent device may be adjusted vertically in conjunction with the needle and other mechanisms. Mounting the various devices on the common bracket 56 makes the adjustment of the several sets of tools convenient. 75

In Fig. 11 the needle and detent mechanisms are shown on a large scale and the latter is shown with its parts connected in 80 a somewhat different position.

It may be desirable to provide tension devices such as is shown in Fig. 12, for the purpose of doing away with the long tension roller 62. The two tension plates 84 85 press against the thread between them and the pressure is adjusted by means of the set nut 87, on the pin 86, regulating the pressure of the spring 85. These tension devices are suitably mounted by a bracket 88, one 90 for each thread, whereby the space intervening between the several tensions is left free. 95

In Figs. 15 and 16 I have shown, diagrammatically, several ways of arranging 95 the needle bars, thread feed, tension and take up, for the purpose of preserving as open a view as possible of the embroidery surface. In Fig. 15, I have shown the take up bar 64, carried upon arms 65, which rock 100 with the shaft 66, and the latter is mounted in front of the needle bar and in such a position that the take up device as a whole will come in substantially the same plane as the needle bar. The support 61^a, for the 105 thread spool is arranged close to and underneath the needle bar 14. The tension roller 62 is here mounted between the spool support and take up. With the thread spools arranged close to and underneath the needle 110 bar the stitching elements are more closely grouped than before and this enables me to arrange the various superimposed needle bars closer than heretofore and still permit the attendant to easily see between the parts 115 and follow the operations of the many needles. The path of vision is indicated by arrows in Fig. 11. In Fig. 16, I also place the thread spool supports 61, immediately below the needle bar in order to give a clear 120 view of the embroidering operations; but in this view I have shown the tension roller 62, arranged just below the thread spools.

In Fig. 10 I have shown the shuttle tracks adjustable to correspond with the 125 adjustability of the needle mechanisms. In the upper part of the view the tracks 17 are connected with the frame 53 by means of the bolts 89 engaging in slots 90 of the frame. The shuttle tracks are thus adjust- 130

able vertically, to bring them in proper relation with the needle mechanisms. The lower part of this view shows another method of adjusting the shuttle tracks. In this form

5 the frame has an interrupted channel 91, in which the blocks 92 of the shuttle tracks travel and a vertical shaft 93 is threaded through the blocks 92. By turning the shaft 93 the shuttle tracks may be vertically adjusted.

10 The present invention I believe to be broadly new and I do not wish to be limited to the exact forms and arrangements herein shown as the broad character of the invention 15 may be followed in various other arrangements.

15 In using the terms vertical frame members and upright frame members I do not use them in a narrow sense but desire that 20 they be given a meaning commensurate with the objects and scope of my invention.

Having described my invention what I claim is:

25 1. An embroidering machine embodying embroidering elements mounted upon a plurality of reciprocating, superimposed bars arranged in longitudinal rows lengthwise of the machine, and a stationary supporting frame, composed of end standards and a plurality of rigid upright frame members arranged at intervals between the end standards, and arranged to connect the said several bars longitudinally and also in vertical relation, said rigid upright frame members 30 supporting the rows of bars at intervals along the machine, and means for supporting the said bars on said rigid frame members whereby they will reciprocate relative thereto, but be supported thereby.

35 40 2. An embroidering machine embodying a plurality of reciprocating, superimposed needle bars arranged in longitudinal rows lengthwise of the machine, and a stationary supporting frame, composed of end standards and a plurality of rigid upright frame members arranged at intervals between the end standards, and arranged to connect the several needle bars longitudinally and also in vertical relation, said rigid upright frame 45 members supporting the rows of needle bars at intervals along the machine, and means for supporting the needle bars on said rigid frame members whereby they will reciprocate relative thereto, but be supported thereby.

50 55 3. An embroidering machine embodying a plurality of shuttle tracks, arranged in a plurality of superimposed rows lengthwise of the machine, and a stationary supporting frame, composed of end standards and a plurality of rigid upright frame members arranged at intervals between the end standards, and arranged to connect the several 55 rows of shuttle tracks longitudinally and also in vertical relation, said rigid upright frame members supporting the rows of

shuttle tracks at intervals along the machine, and means for connecting said end standards and said rigid upright frame members longitudinally in a rigid whole.

4. An embroidering machine embodying a 70 plurality of reciprocating, superimposed needle bars arranged in longitudinal rows lengthwise of the machine, and a stationary supporting frame, composed of end standards and a plurality of rigid upright frame 75 members arranged at intervals between the end standards, and arranged to connect the several needle bars longitudinally and also in vertical relation, said rigid upright frame members supporting the rows of needle bars 80 at intervals along the machine, means for supporting the needle bars on said rigid frame members whereby they will reciprocate relative thereto but be supported thereby and means supported by said rigid upright frame members and adapted to support thread supplying elements underneath and close to, the said needle bars, to give an unobstructed view of the embroidering operations.

85 5. An embroidering machine comprising a frame embodying end standards and stationary intermediate upright frame sections disposed at intervals along the machine, means uniting the said sections in a rigid 90 whole, embroidering elements arranged in longitudinal superimposed rows and independently supported upon said upright frame sections whereby their weight will be carried thereby at intervals along the machine, said rows of embroidering elements 95 being individually and vertically adjustable on the upright frame sections, whereby the rapport rows may be spaced varying distances apart.

100 105 6. An embroidering machine comprising a rigid frame embodying end standards and stationary intermediate upright frame sections disposed at intervals along the machine, means uniting said sections in a rigid 110 whole, embroidering elements arranged in longitudinal superimposed rows, said rows being independently supported upon the upright frame sections whereby their weight will be carried thereby at intervals along 115 the machine, said rows of embroidering elements being individually and vertically adjustable on the upright frame sections, driving mechanism supported on the upright frame sections and means for adjusting the 120 connection between the rows of embroidering mechanism and the driving mechanism.

125 7. An embroidering machine comprising a stationary frame embodying end standards and stationary intermediate upright frame sections disposed at intervals along the machine, means uniting said sections in a rigid whole, embroidering elements arranged in longitudinal superimposed rows, bars on which the several rows of embroider- 130

ing mechanism are supported, said bars being supported upon the upright frame sections whereby their weight will be carried thereby at intervals along the machine, said 5 bars being individually and vertically adjustable on the upright frame sections whereby the various rows of embroidering elements may be spaced at varying distances, means for operating the embroidering 10 elements and means for adjusting the operating means to permit of the adjustment of the embroidering elements.

8. An embroidering machine comprising a stationary frame embodying end standards 15 and intermediate stationary upright frame sections disposed at intervals intermediate the end standards, means uniting the frame sections in a rigid whole, a plurality of embroidering devices, such as 20 needle bars, tension, etc., each arranged in a plurality of longitudinal rows, means for supporting the embroidering elements of the several rows on said upright frame sections at various points whereby their weight 25 will be carried at intervals by the frame sections and common to the several kinds of embroidering devices of a row, said supporting means being adjustable on the upright frame sections whereby the embroidering 30 devices of the several rows may be vertically adjusted and whereby the several rows may be adjusted independently of each other.

9. An embroidering machine comprising 35 a frame embodying stationary upright frame members, brackets on the upright frame members and take up, tension and needle mechanism mounted on said brackets, said brackets being adjustable upon the 40 upright frame members, whereby the position of the needle, tension and take up devices may be simultaneously adjusted on the frame.

10. An embroidering machine comprising 45 a frame embodying upright frame members arranged along the machine, means uniting the same, and a longitudinal needle bar having lateral shafts, a tension and take up having shafts, and brackets in which the shafts of the needle, tension and 50 take up devices are journaled, said brackets being common to the several devices and adjustably supported by the upright frame members.

11. An embroidering machine comprising 55 a frame embodying end standards and intermediate stationary upright frame members, means uniting the upright frame members in a rigid whole, longitudinal superimposed needle bars supported at intervals along the machine by said upright frame members, the several needle bars being vertically adjustable on the upright frame members, longitudinal superimposed shuttle tracks supported at intervals on said 60 upright frame members and vertically adjustable thereon.

12. An embroidering machine comprising 65 a frame embodying upright frame members arranged at intervals along the machine, means uniting the same in a rigid whole, longitudinal shuttle tracks supported on the upright frame members and having threaded blocks, and threaded upright shafts engaging the threaded blocks 70 of the shuttle tracks, said shafts being adapted to effect the vertical adjustment of the said shuttle tracks.

Signed at St. Gall, in the Canton of St. Gall, Switzerland, this 3rd day of February, 1910.

MORRIS SCHOENFELD.
